UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF NEW JERSEY.

TYPE-WRITING MACHINE.

No. 853,242.

Specification of Letters Patent.

Patented May 14, 1907.

Application filed December 28, 1906. Serial No. 349,771.

To all whom it may concern:

Be it known that I, WILLIAM F. HELMOND, a citizen of the United States, residing in Hartford, in the county of Hartford and 5 State of Connecticut, have invented certain new and useful Improvements in Type-Writing Machines, of which the following is a specification.

This invention relates to stops for limiting 10 the travel of carriages of typewriting machines and particularly to the stops which regulate the width of the left hand margin on the page of writing.

In the well known Underwood typewriting 15 machine, the adjustable stop upon the framework which limits the return movement of the carriage to begin a new line, has a range of adjustment which is only about half the range of travel of the carriage; and it is one 20 of the objects of my invention to effect a substantial increase in the width of the left hand margin on the sheet obtainable on said machine. To this end, I provide upon the carriage, in addition to the usual stop, an auxiliary stop which can be brought into use at 25 will, to engage the margin stop upon the machine frame at a point considerably in advance of the usual stop upon the carriage, whereby the range of travel of the carriage 30 is greatly reduced and a correspondingly greater left hand margin obtained upon the sheet. I provide means for mechanically detaining the auxiliary stop in either effective or ineffective position at will, so that it may be thrown out of use when not needed. Both 35 stops upon the carriage are releasable by a single release key, and both are constructed to ride freely over the framework stop during the run of the carriage in letter feeding direction.

Other features and advantages will hereinafter appear, and it will be understood that the improvements are adapted for other purposes, and that the invention may be embodied in many different forms.

In the accompanying drawings, Figure 1 is a perspective view of the upper front part of an "Underwood" typewriting machine, showing the carriage arrested by the auxiliary stop. Fig. 2 is a front view illustrating the carriage arrested by the usual stop; the auxiliary stop being shown however in effective position. Fig. 3 shows the two stops on the carriage released by depression of the

release key. Fig. 4 shows the auxiliary stop 55 locked out of effective position. Fig. 5 is a sectional side elevation of the stop mechanism.

In said machine, type-bars 1 strike against the front side of a platen 2, Fig. 5, the latter mounted upon a carriage 3 connected by a strap 4 to a spring-barrel 5 which pulls the carriage in letter feeding direction; the carriage having a roll 6 to run upon a rail 7. Upon the rail 7 is usually provided a rack 8 65 engageable by a tooth 9 provided in a carrier 10 mounted partly upon the rod 7 and partly upon a front rod 11 and having a margin stop 12, which is in the path of the stop 13 upon the carriage. The carrier 10 is releasable by 70 means of a handle 14, so that it may be adjusted in the direction of the travel of the carriage; but its range of adjustment is limited by collars 15 which support the rod 11, so that the width of the left hand margin on 75 the sheet is somewhat restricted. A pointer or an index 16 upon the stop carrier 10 cooperates with a scale 17 upon the framework to guide the operator in setting the margin stop. An index 18 upon the carriage co- 80 operates the same scale to indicate the progress of the carriage.

The stop 13 is mounted upon an arm 19 pivoted at 20 upon the front bar of the carriage, and from said pivoted arm 20 extends 85 to the extreme right hand end of the carriage, and carries at its end a release key 21, whereby the stop 13 may be lifted clear of the margin stop 12, Fig. 3; the arms 19, 20 forming a lever of the first order. As so far described the parts are in common use upon 90 said Underwood machine.

I provide upon the carriage an auxiliary stop 22, to engage said margin stop 12 at a point two or three inches in advance of the 95 usual stop 13, thereby increasing to that extent the width of left hand margin obtainable upon the sheet. Said stop 22 is formed upon the right hand end of an arm 23 pivoted at 24 upon the arm 19 between the pivot 20 100 and the stop 13. A spring 25 fixed by a screw 26 upon the arm 23 bears at its free end up against a ledge 27 formed upon the carriage bar, and presses down constantly both arms 23 and 19, so as to hold both stops 22 and 13 105 in effective positions. By means of a handle 28 pivoted at 29 upon an arm 30 extending to the left from the pivot 24, the stops 22

may be rendered either effective or ineffective at will; a cam 31 being provided upon said finger-piece 28 to engage the under side of the carriage ledge 27, to press and hold 5 down the arm 30 and elevate the arm 23 and stop 22 above the margin stop, Fig. 4; the arms 30 and 23 forming a lever of the first order. When the finger-piece 28 is swung the other way, Fig. 2, the cam 31 is released 10 and the lever 30, turned by the spring 25 until the stop 22 is depressed sufficiently to engage the margin stop 12; the turning movement of said lever being limited by a shoulder 32 formed upon the handle 28 to 15 bear against the ledge 27. The right hand end of the arm 19 is normally pressed by the spring 25 up against the under side of said ledge 27 as at 20^a, Fig. 2. A stop 33 limits the play of the handle 28.

20 When the handle 28 is at the Fig. 4 position, the stop 22 is out of use, but when it is swung to the position seen at Figs. 1, 2 and 3, the stop 22 is in use and engages the margin stop 12 to reduce the range of travel of 25 the carriage and increase the left hand margin on the sheet. The distance between the stops 22 and 13 may be equal to two or three of the major divisions 34 on the scale 17 so that the operator may readily set the index 30 16 to the point required for the extra wide margin. If it is desired at any time to write in such wide margin, it is only necessary to press the key 21, Fig. 3, whereby the pivot 24 is carried up and the arm 23 is 35 swung up about the point of contact of the shoulder 32 with the ledge 27, so that the stop 22 clears the margin stop 12. It will be understood that the operator may thereupon either hold the release key 21 down until the 40 carriage has been moved to the extreme right, or may permit said release key to rise so that the stop 13 may engage the margin stop 12, thereby mechanically determining a submarginal point for beginning the line of 45 writing in the main margin. If the release key be depressed when the stop 22 is thrown off, as at Fig. 4, said stop 22 rises idly and again drops to the Fig. 4 position when the release key rises.

50 In said Underwood typewriting machine, the engaging face 12^a of the stop 12 is undercut as illustrated, so as to prevent the stop 13 from jumping up when it engages the stop 12. The stop 22 is shaped to correspond 55 with the face 12^a of the stop 12; and a nose 22^a may be provided to prevent the stop 22 from sliding down along the face 12^a when the stops engage each other.

Having thus described my invention, I 60 claim:

1. In a typewriting machine having a framework and a carriage, the combination of a stop upon the framework, a stop upon the carriage to co-operate with the first stop 65 to arrest the return movement of the car-

riage to begin a new line of writing, one of said stops being adjustable to regulate the width of the left-hand margin on the page of writing, a stop interposable between said stops to serve as a substitute for one thereof 70 and co-operate with the other thereof to reduce substantially the range of movement of the carriage and cause a substantial increase in the width of the left-hand margin on the page, a key having means to release 75 the carriage from the control of all of said stops, and a stop-restoring spring to oppose the releasing action of said key.

2. In a typewriting machine having a framework and a carriage, the combination 80 of a stop upon the framework, a stop upon the carriage to co-operate with the first stop to arrest the return movement of the carriage to begin a new line of writing, one of said stops being adjustable to regulate the 85 width of the left-hand margin on the page of writing, a stop interposable between said stops to serve as a substitute for one thereof and co-operate with the other thereof to reduce substantially the range of movement of 90 the carriage and cause a substantial increase in the width of the left-hand margin on the page, means for mechanically detaining said interposable stop either in or out of a position of use, at will, a key having means to 95 release the carriage from the control of all of said stops, and a stop-restoring spring to oppose the releasing action of said key.

3. In a typewriting machine having a framework and a carriage, the combination 100 of a stop upon the framework, a stop upon the carriage to co-operate with the first stop to arrest the return movement of the carriage to begin a new line of writing, one of said stops being adjustable to regulate the 105 width of the left-hand margin on the page of writing, a stop interposable between said stops to serve as a substitute for one thereof and co-operate with the other thereof to reduce substantially the range of movement of 110 the carriage cause a substantial increase in the width of the left-hand margin on the page, and means for releasing the carriage from the control of all of said stops, and a stop-restoring spring to oppose the action of 115 said releasing means.

4. In a typewriting machine having a framework and a carriage, the combination 120 of a stop upon the framework, a stop upon the carriage to co-operate with the first stop to arrest the return movement of the carriage to begin a new line of writing, one of said stops being adjustable to regulate the width of the left-hand margin on the page of writing, a stop interposable between said 125 stops to serve as a substitute for one thereof and co-operate with the other thereof to reduce substantially the range of movement of the carriage and cause a substantial increase in the width of the left-hand margin on the 130

- page, means for mechanically detaining said interposable stop either in or out of a position of use, at will, means for releasing the carriage from the control of all of said stops, 5 and a stop-restoring spring to oppose the action of said releasing means.
5. In a typewriting machine having a framework and a carriage, the combination with a stop adjustable along one of said parts, 10 of a plurality of stops mounted upon the other of said parts to co-operate with the first stop upon the return of the carriage to begin a new line of writing, to regulate the width of the left hand margin on the sheet, a 15 key connected to said plurality to move them out of the path of the first stop, and a stop-restoring spring to oppose the action of said key.
6. In a typewriting machine having a framework and a carriage, the combination with a stop adjustable along one of said parts, 20 of a plurality of releasable stops mounted at intervals upon the other of said parts, either member of said plurality to co-operate with the adjustable stop at will upon the return of the carriage to begin a new line of writing, 25 to regulate the width of the left-hand margin on the sheet, a key for releasing both of said releasable stops, a spring to restore both 30 stops upon the release of said key, and means for locking a single member of said plurality out of use.
7. In a typewriting machine having a carriage member and a framework member, the combination of a stop adjustable along one 35 of said members, and two stops pivotally mounted upon the other of said members to co-operate with said stop to arrest the carriage at either one of two points in its return 40 movement to begin a new line; the carriage being releasable from the control of said pivoted stops, and the latter being constructed to turn upon their pivots to ride over the adjustable stop during the movement of the 45 carriage in letter-feeding direction.
8. In a typewriting machine having a carriage member and a framework member, the combination of a single stop upon one 50 end of said members and two stops upon the other of said members to co-operate with said single stop to arrest the carriage at either one of two points in its return movement to begin a new line; the carriage being releasable from the control of all of said stops to 55 permit writing in the left hand margin on the page; and the two stops being yielding relatively to the single stop, to permit free subsequent movement of the carriage in letter-feeding direction.
- 60 9. In a typewriting machine having a framework and a carriage and provided with a stop upon the framework, the combination of two stops upon the carriage, to co-operate with the framework stop to arrest the carriage at either one of two points in its re- 65
- turn movement to begin a new line, and a key upon the carriage for releasing its stops from the framework stop; the carriage and framework stops being relatively yielding to permit movement of the carriage in letter- 70 feeding direction.
10. In a typewriting machine having a framework and a carriage and provided with a stop upon the framework, the combination of two stops upon the carriage, to co-operate with the framework stop to arrest the carriage at either one of two points in its return movement to begin a new line, and a key upon the carriage for releasing its stops from the framework stop; the stops upon the carriage constructed to yield to ride over the framework stop when the carriage moves in letter feeding direction, and means being provided upon the carriage for detaining one of its stops in either effective or ineffective 80 position at will.
11. In a typewriting machine having a framework and a carriage, the latter provided with a stop to co-operate with a stop upon the framework to arrest the carriage in its return movement to begin a new line, 85 a lever being mounted upon said carriage to release the carriage stop, the combination of an auxiliary stop mounted upon the carriage to arrest the latter at a point in advance of the first-mentioned carriage stop, and means for enabling said lever to release said auxiliary stop; both stops upon the carriage being constructed to ride over the framework stop while the carriage moves in letter feeding 90 direction.
12. In a typewriting machine having a framework, the combination of a carriage, the latter provided with a stop to co-operate with a stop upon the framework to arrest the carriage in its return movement to begin a new line, 95 a lever being mounted upon said carriage to release the carriage stop, an auxiliary stop mounted upon the carriage to arrest the latter at a point in advance of the first-mentioned carriage stop, and means for enabling said lever to release said auxiliary stop; both stops upon the carriage being constructed to ride over the framework stop while the carriage moves in letter feeding 100 direction, and a finger piece having a cam to lock said auxiliary stop out of effective position.
13. In a typewriting machine having a carriage, the combination of a framework, 105 and a stop upon the framework adjustable in the direction of travel of the carriage for regulating the left hand margin upon the sheet, the range of adjustment of said stop being substantially less than the range of 110 travel of the carriage, a device in the form of a lever being pivoted upon the carriage and having at one end a release key and at the other end a stop to engage said margin stop, an auxiliary stop mounted upon the carriage 115

to engage said margin stop at a point substantially in advance of said carriage stop, and means for enabling the release key to release said auxiliary stop.

14. In a typewriting machine having a carriage, the combination of a stop upon the framework adjustable in the direction of travel of the carriage for regulating the left-hand margin upon the sheet, the range of adjustment of said stop being materially less than the range of travel of the carriage, a device in the form of a lever being pivoted upon the carriage and having at one end a release key and at the other end a stop to engage said adjustable stop, to arrest the carriage during the return thereof to begin a new line, a device in the form of a second lever pivoted upon the first lever between the pivot and stop of the latter, and a stop upon said second lever in position to engage said margin-stop during the return of the carriage, whereby the range of regulation of the left-hand margin on the page is increased according to the distance between the stops on the carriage.

15. In a typewriting machine having a carriage, the combination of a stop upon the framework adjustable in the direction of travel of the carriage for regulating the left-hand margin upon the sheet, the range of adjustment of said stop being materially less than the range of travel of the carriage, a device in the form of a lever being pivoted upon the carriage and having at one end a release key and at the other end a stop to engage said adjustable stop, to arrest the carriage during the return thereof to begin a new line, a device in the form of a second lever pivoted upon the first lever between the pivot and stop of the latter, and a stop upon said second lever in position to engage said margin-stop during the return of the carriage, whereby the range of regulation of the left-hand margin on the page is increased according to the distance between the stops on the carriage; and a spring upon the second lever bearing upon the carriage to maintain both stops on the carriage in working positions; each of said stops on the carriage being constructed to ride freely over the adjustable stop during movement of the carriage in letter feeding direction.

16. In a typewriting machine having a carriage, the combination of a stop upon the framework adjustable in the direction of travel of the carriage for regulating the left-hand margin upon the sheet, the range of adjustment of said stop being materially less than the range of travel of the carriage, a device in the form of a lever being pivoted upon the carriage and having at one end a release key and at the other end a stop to engage said adjustable stop, to arrest the carriage during the return thereof to begin a new line, a device in the form of a second lever pivoted

upon the first lever between the pivot and stop of the latter, and a stop upon said second lever in position to engage said margin-stop during the return of the carriage, whereby the range of regulation of the left-hand margin on the page is increased according to the distance between the stops on the carriage; and a spring upon the second lever bearing upon the carriage to maintain both stops on the carriage in working positions; each of said stops on the carriage being constructed to ride freely over the adjustable stop during movement of the carriage in letter feeding direction; and said first lever being operative to lift both of said stops on the carriage free of said margin-stop, to permit writing in the right-hand margin on the sheet.

17. In a typewriting machine having a carriage, the combination of a stop upon the framework adjustable in the direction of travel of the carriage for regulating the left-hand margin upon the sheet, the range of adjustment of said stop being materially less than the range of travel of the carriage, a device in the form of a lever being pivoted upon the carriage and having at one end a release key and at the other end a stop to engage said adjustable stop, to arrest the carriage during the return thereof to begin a new line, a device in the form of a second lever pivoted upon the first lever between the pivot and stop of the latter, and a stop upon said second lever in position to engage said margin-stop during the return of the carriage, whereby the range of regulation of the left-hand margin on the page is increased according to the distance between the stops on the carriage; and a device for silencing said second stop on the carriage consisting of a cam pivoted on said second lever and provided with a friction washer and a handle, and constructed to bear against a part of the carriage to lock said second stop on the carriage out of working position.

18. In a typewriting machine having a carriage, the combination of a stop upon the framework adjustable in the direction of travel of the carriage for regulating the left-hand margin upon the sheet, the range of adjustment of said stop being materially less than the range of travel of the carriage, a device in the form of a lever being pivoted upon the carriage and having at one end a release key and at the other end a stop to engage said adjustable stop, to arrest the carriage during the return thereof to begin a new line, a device in the form of a second lever pivoted upon the first lever between the pivot and stop of the latter, and a stop upon said second lever in position to engage said margin-stop during the return of the carriage, whereby the range of regulation of the left-hand margin on the page is increased according to the distance between the stops on the car-

riage; and a device for silencing said second stop on the carriage consisting of a cam pivoted on said second lever and provided with a friction washer and a handle, and constructed to bear against a part of the carriage to lock said second stop on the carriage out of working position; a lip being formed on the second stop on the carriage to catch over the margin-stop, to prevent said second stop from being forced down along the margin-stop at the impact of the stops.

19. In a typewriting machine having a carriage, the combination of a stop upon the framework adjustable in the direction of travel of the carriage for regulating the left-hand margin upon the sheet, the range of adjustment of said stop being materially less than the range of travel of the carriage, a device in the form of a lever being pivoted upon the carriage and having at one end a release key and at the other end a stop to engage said adjustable stop, to arrest the carriage during the return thereof to begin a new line, a device in the form of a second lever pivoted upon the first lever between the pivot and stop of the latter, and a stop upon said sec-

ond lever in position to engage said margin-stop during the return of the carriage, whereby the range of regulation of the left hand margin on the page is increased according to the distance between the stops on the carriage; a spring upon the second lever bearing upon the carriage to maintain both stops on the carriage in working positions; each of said stops on the carriage being constructed to ride freely over the adjustable stop during movement of the carriage in letter feeding direction, and said first lever being operative to lift both of said stops on the carriage free of said margin-stop, to permit writing in the right-hand margin on the sheet; and a device for silencing said second stop on the carriage consisting of a cam pivoted on said second lever and provided with a friction washer and a handle, and constructed to bear against a part of the carriage to lock said second stop on the carriage out of working position.
